Design of a
Bracket
By Irah Chase Jr.

Des. 949

Iraah Chase Jr. of Boston Mass.
Letters Patent No 949. Dated Oct 13th 1857

The schedule referred to in these Letters Patent is making part of the same.

To all whom it may concern:

Be it known that I, Iraah Chase Jr. of the City of Boston, County of Suffolk and State of Massachusetts, have invented or produced a new & original Design for a Shelf Bracket, and I do hereby declare that the following is a full and exact description of the same.

Fig. 1. represents the design in detail, with the edge and scroll work with the Griffin head combined.

What I claim as my invention or production, is the peculiar configuration of the Griffin head & scroll work as shown in the drawing.
